UNITED STATES PATENT OFFICE.

SHERRARD EWING, OF BRONXVILLE, NEW YORK, ASSIGNOR TO NATIONAL ASSOCIATION OF TRAVELERS AID SOCIETIES, OF NEW YORK, N. Y., A CORPORATION OF WEST VIRGINIA.

DESIGN FOR A BADGE.

Application filed November 25, 1924. Serial No. 11,471. Term of patent 14 years.

To all whom it may concern:

Be it known that I, SHERRARD EWING, a citizen of the United States, residing at 21 Maple Street, Bronxville, in the county of Westchester and State of New York, have invented a new, original, and ornamental Design for Badges, of which the following is a specification, reference being had to the accompanying drawings, forming part thereof.

In the drawing, Fig. 1 is a plan view of

a badge, showing my new design, the outer rim being in red with gold edging, the link, chain, words and latitude and longitude lines in gold, and the land portions of the two hemispheres indicated, in blue, and Fig. 2 is an edge view of the badge.

I claim:

The ornamental design for a badge, as shown and described.

SHERRARD EWING.
